Primary Examiner — Lauren D McVey*(74) Attorney, Agent, or Firm* — Bayramoglu Law Offices, LLC(57) **CLAIM**

The ornamental design for a signal acquisition controller, as shown and described.

DESCRIPTION

FIG. 1 is a front, right and top perspective view of a signal acquisition controller showing our new design;

FIG. 2 is a rear, right and bottom perspective view thereof;

FIG. 3 is a front view thereof;

FIG. 4 is a rear view thereof;

FIG. 5 is a top view thereof;

FIG. 6 is a bottom view thereof; and,

FIG. 7 is a right side view thereof, a left view being a mirror image of the right side view.

The broken lines depict portions of the signal acquisition controller that form no part of the claimed design.

1 Claim, 7 Drawing Sheets(56)
